UNITED STATES PATENT OFFICE.

AUGUST DIETZ, OF NEW YORK, N. Y., ASSIGNOR TO HIMSELF AND E. J. DE SMEDT, OF SAME PLACE.

IMPROVEMENT IN ROTARY ENGINES.

Specification forming part of Letters Patent No. 154,231, dated August 18, 1874; application filed May 16, 1874.

To all whom it may concern:

Be it known that I, AUGUST DIETZ, of the city, county, and State of New York, have invented a new and Improved Rotary Engine, of which the following is a specification:

In the accompanying drawing, Figure 1 represents a vertical transverse section, on line *c c* of Fig. 2, of my improved rotary engine, showing steam-distributing piston-valve; Fig. 2, a vertical longitudinal section on line *k k*, Fig. 1; Fig. 3, a vertical transverse section on the line *x x*, Fig. 2, showing exhaust-valve of piston; Fig. 4, a front view of the engine, showing spring-connection of slide-pieces; and Figs. 5 and 6, respectively, are detached side and front views of the induction and distribution valve of piston.

Similar letters of reference indicate corresponding parts.

My invention relates to improvements in rotary engines with variable cut-off; and consists of a cylindrical casing with radial spring slides or wings, which are suitably packed and acted upon by the elliptic piston, rotating tightly therein by means of combined spring and steam-packed strips. The piston is keyed to the hollow shaft, through which the steam enters, and provided with variable cut-off and distribution valve at one side, and with an exhaust-valve at the opposite side, both being closely pressed against the cylinder-heads by spring and steam packing devices. The ports of this distribution-valve conduct the steam through entrance-ports of one cylinder-head into the interior of the engine, where it causes the rotation of the piston in connection with the spring-slides, exhausting the steam simultaneously therewith by perforations of the piston at opposite sides from the parts acted upon, being then conducted through the exhaust-valve and ports of the opposite cylinder-head to the exhaust-pipe.

In the drawing, A represents the cylinder of my rotary engine, which is provided with three longitudinal and equidistant openings, *A*¹, for guiding the spring slides or wings B in radial direction therein. The spring-slides B are tightly packed in the longitudinal guide-openings *A*¹ by suitable stuffing-boxes *a*, in

order to prevent the escape of steam by the wearing out of the slides. Extension casings or boxes *B*¹ are cast or otherwise applied to cylinder A, for closing the same completely toward the outside. The piston C is of double-eccentric or elliptical shape and keyed to the hollow steam-entrance shaft D, which rotates by means of tight stuffing-boxes *D*¹ in the cylinder-heads *A*² *A*³. Both face-sides of the piston are cylindrically recessed for receiving the sliding metal boxes or valves E E', of which the former serves for the entrance and distribution of the steam, the opposite one for exhausting the steam from the cylinder. The piston C is provided, at the extreme points of contact with the cylinder A, with longitudinal rectangular grooves or recesses *b*, for receiving the metal packing-strip *b*¹. Face-grooves *b*² form the side extensions of recesses *b*, and receive the extension-tongues *d* of the sliding valves E E'. The top and bottom grooves *b* are further arranged in radial direction with perforations *e*, in which slide the spiral springs *e*¹, with base pistons *e*². The perforations *e* communicate, by small bottom holes *e*³, with the chambers of the slide-valves E E', and receive from them the required steam-pressure for forcing the packing strips *b* close against inner periphery of the cylinder during the rotation of the piston. The central connecting part of the piston, intermediate between slide-valves E E', is in similar manner perforated in longitudinal direction by holes *f*, with spring *f*¹ and balance-pressure holes *f*², through which the steam enters toward the rear part of the valves E E', and packs them closely with their face parts against the heads of the cylinder, producing thus a continuous steam-tight fitting thereon. A series of holes, *g*, is furthermore drilled at the exhaust side of the piston at diametrically opposite points, through which the expanded steam is conducted from the cylinder to the exhaust-valve E'. The induction and distribution valve E has an interior cylinder, *h*, of larger diameter than the hollow shaft, provided with slotted recesses *h*¹ at the circumference, of which each recess communicates with a separate chamber or port, *h*², formed by radial partitions *h*³.

These ports are arranged diametrically opposite to each other, as shown in Figs. 5 and 6, and slide along the front cylinder-head in such a manner that always two corresponding ports are closed thereby. The induction-ports are opened or closed by a segment-piston, F, sliding in the interior cylinder h of the distribution-valve E, and being operated by a connecting-valve rod, i, whose diametrical piston-arms i^1 move in corresponding slots i^2 of the hollow shaft.

A second smaller piston, F', is attached to inner end of valve-rod i, sliding in the hollow shaft, and serving, by the steam-pressure thereon, to open one or all of the induction-ports of valve E. Piston F' serves also for closing, by drawing out the piston-rod far enough, the shaft-apertures l, which lead into the exhaust-valve E', for packing the same tightly on its cylinder-head. The segment-piston F closes, at the same time, the induction-ports in the distribution-valve E, so that the pistons may jointly act as a throttle-valve, which may be connected and operated readily with a horizontal or vertical governor.

The exhaust-valve E' is constructed in similar manner as valve E, with an interior cylinder, but without recesses, and has only two separate and diametrically-opposite chambers or exhaust-ports, into which the exhaust perforations of the piston open.

The front cylinder-head A¹ is cast with distribution channels or ports m, which connect with the openings of the induction-ports of the distribution-valve E, while the rear cylinder-head A³ has exhaust-ports m¹, through which the expanded steam is carried off by a suitable exit-aperture, m², as shown in Fig. 2. The cylinder-heads A² A³ are firmly and tightly bolted on the body of the cylinder, and provided with thicker rims or flanges, through which pass the adjustable rods n, for connecting the spring slide-pieces B with spring rings or cams G. Rods n have hook-shaped ends n', by which they are firmly held on the spring-rings G, so that the spring-slides B are always firmly pressed with their rounded-off corner ends on the piston, while their ends slide in corresponding side grooves B² of the cylinder-heads. These side or guide grooves are, in similar manner as the other parts of the engine, packed by stuffing-boxes, which may be suitably regulated from the outside by set-screws passing through the cylinder-heads, in order that the wearing out of the flanges is overcome.

The operation of the engine is as follows: Live steam is introduced, through a stuffing-box and governor arrangement, to the hollow shaft, and passes, first, through the piston-rod slots and slots i^2 and l, into the slide-valves E E', for pushing the same against the cylinder-heads, and forces, also, the packing-strips b of the piston tightly on the cylinder. The steam enters then, through the slotted induction-recesses of the induction-

valve E, into the ports of the same, and from them, through the connecting-ports of the front cylinder-head, into the inside of the cylinder, acting there simultaneously at opposite points on the piston by means of the compartments formed between the spring-slides and the extreme points of the piston. The compartments on the opposite sides of the slides serve for exhausting the expanded steam through the exhaust-holes of the piston. Every rotation of the piston (which is exposed three times to the action of live steam in passing the connecting-ports of the front head) is produced by six steam-inductions, which may be increased by opening the additional recesses, exhausting in the same manner without counter-pressure. The exhaust steam passes off, through the opposite valve E' and the connecting exhaust-ports of the cylinder-head A³, to the exhaust-pipe, the passage of the steam being indicated by arrows in the various figures.

For the purpose of working the engine expansively, the outside end of the piston-rod is applied to a screw-wheel or lever for closing the innermost, or two innermost, induction-apertures of the distribution-valve E, so that no steam can enter into their chambers or ports, causing their blind passage along the ports of the cylinder-head by the action of the expansion of the steam, until the piston is on the balanced position at the beginning of the exhaust. This expansive action of the steam is represented by a diagram in Fig. 1, and repeats itself six times in every complete revolution, so that dead-points are entirely overcome.

Having thus described my invention, I claim as new and desire to secure by Letters Patent—

1. The combination of cylinder A, radial spring slide-pieces B, hollow shaft D, elliptical piston C, sliding steam-packed induction and exhaust valves E E', and cylinder-heads A² A³, provided with valve-connecting ports m and m¹, all arranged and constructed substantially in the manner and for the purpose specified.

2. In the double-eccentric or elliptical piston C, the combination of the longitudinal packing-strips, the exhaust-holes g, and the cylindrical end cavities, substantially as and for the purpose specified.

3. The combination of the self-adjusting valves E E' and their ports h¹ h², the longitudinal spiral springs, the cylinder-heads, with their ports m m¹, and the piston C, substantially as and for the purpose specified.

4. The combination of the induction-valve E with the segment-piston F, piston F', and rod i, for the purpose of forming a cut-off for the steam, substantially as and for the purpose specified.

5. The exhaust-valve E', having chambers or ports formed by radial partitions, in combination with the exhaust perforations g of the

piston C, and the communicating chambers m^1 of cylinder-head A³, for conducting the expanded steam to the exhaust-pipe, substantially as and for the purpose specified.

6. The combination of the radial spring slide-pieces B, the connecting-rod n' , and the outer spring-rings G, all operating together

to hold the pieces B tight against the piston C, substantially as and for the purpose specified.

AUGUST DIETZ.
